GYRATORY VALVE DISK

George H. Molden, Bridgeport, Conn., assignor to
The Sprague Meter Company, Bridgeport,
Conn., a corporation of Connecticut

Application August 10, 1940, Serial No. 352,067

8 Claims. (Cl. 251—160)

This invention relates to improved constructions in composite valve disks of the general type disclosed in my United States Patent No. 1,586,685, granted June 1, 1926. The centrally apertured body of such a disk gyrates edgewise so that its bottom flat face constantly wipes against the co-planar valve seat forming edges of upstanding partitions bordering around the mouths of adjacent vertical passageways which give to and from the various measuring chambers of the Sprague type of gas meter. Certain inner and outer circumferential edges of the disk thus pass over and successively cover and uncover these passageway mouths in a manner to govern the sequence and relative rates of flow with which gas is taken into and let out of the measuring chambers.

My former said patent emphasizes the importance of lightness of weight and simplicity of construction in a composite valve disk for this purpose, the body part of which disk may comprise a flat faced ring or apertured disk of glass or other suitable material preferably thick enough to be self rigid, and another of whose parts may comprise preferably a light weight cap of thin sheet material as for instance pliant metal overlying and secured against the top face of the glass ring and spanning or roofing over the central aperture therein. In actual practice it has proven desirable to stiffen the thin horizontal diaphragm-like portion or roof wall of such cap by employing extra reinforcing parts in order more firmly to support a crank pin impelled boss by which the disk is gyrated. However, the use of such extra parts objectionably increases weight and complicates assembly. Also in prior constructions, oil and foreign substances lodging on top of the cap have been able to work their way down over the peripheral cap edge and thereby accumulate on and foul the valve seat forming edges or partition tops which are swept by the bottom or seat wiping surface of the glass ring.

One object of the present improvements is to render the diaphragm-like roof wall of the thin metallic cap sufficiently stiff and rigid for its force transmitting duty without resorting to extra reinforcing parts.

A further object is to maintain a generally horizontal disposition of the diaphragm-like roof wall of the cap in order to conserve vertical space. The small vertical height which is available prohibits forming the cap into a dome-like shape for strengthening such roof wall.

A related object is to prevent buckling of said

diaphragm-like roof wall into oblique inclination to true horizontal when impelling force for gyrating the disk edgewise is applied to the before mentioned crank impelled boss.

5 A further object is to employ stiffening means which at the same time shall provide a retaining pocket or pockets for catching and holding deposits of oil or foreign substance that may find their way onto the top of the disk cap, so that such deposits will be prevented from working their way radially outward to and down over the edge of the disk and thus onto the valve seat forming edges of the partition tops.

10 A further object is to provide the cap member of the composite disk with additional means to retain vagrant lubricating material and foreign deposits which may have escaped the aforesaid retaining pockets before centrifugal force, resulting from gyratory movement of the disk, shall have urged such foreign substances as far outward as the edge of the disk.

15 The foregoing and related objects of the invention will become clear from the following description of a preferred form of the present improvements in which description reference is made to the accompanying drawing wherein:

20 Fig. 1 is a plan view smaller than actual size looking downward on a gas meter of the Sprague type showing the head wall broken away to expose the gyrating valve disk which controls the intake and outlet of gas to and from the measuring chambers of the meter.

25 Fig. 2 is a front view of the top portion of the meter showing certain of the interior construction and parts in section on the plane 2—2 in Fig. 1.

30 Fig. 3 is a plan view of the composite valve disk embodying the present improvements removed from the meter of Fig. 1 and drawn on a scale larger than the preferred actual size.

35 Fig. 4 is a view taken in section on the plane 4—4 in Fig. 3, showing in broken lines the crank by which the valve disk is gyrated.

40 In Figs. 1 and 2 the typical parts of a Sprague type of gas meter correspond to those shown in the U. S. Patent No. 722,390, granted to H. H. Sprague, wherein the main casing 10 of the meter is capped by a hollow head structure 11 into which gas enters through suitable piping (not shown) connecting with inlet 12, and out of which gas departs through suitable piping (not shown) connecting with outlet 13. Within the head 11 suitable mechanism 14, which it will not here be necessary to describe in detail, connects with and operates the register 15 of the meter.

Such register will be understood to include the usual dials and movable pointers which indicate the amount of gas that has passed through the meter. A crank-like finger 18 projects from the mechanism 14 in the path of gyratory travel of upstanding boss head 19 which forms a part of the composite valve disk indicated as a whole by 20.

Composite disk 20 includes a flat faced ring 21 of glass whose bottom surface is finely ground to make a sliding gas tight seal with the coplanar top seat edges of interjoined upstanding partition walls 22 which separate, and border around, the mouths 23 of various passageways 24. These passageways are in free communication with various measuring chambers such as 27 in the meter casing 10, which chambers are separated by reciprocal flexible diaphragms such as 28.

Centrally of the meter casing 10 there is fixed a vertical bearing bracket 29 in which is journaled a vertically extending shaft 30, only the upper end of which is shown in Fig. 2 as carrying the crank arm 31 whose free end carries the upstanding crank pin 32. This pin pivotally engages within a downwardly opening socket 33 in the boss 34. The top end of the latter affords the before mentioned projection 19 for driving the crank finger 18 to operate the register 15 of the meter. While no connections are herein shown for transmitting movement from the meter diaphragms 28 to the vertical shaft 30, it will be understood that the same may take any conventional form whereby sequentially related reciprocal movements of plural diaphragms caused by gas moving into and out of the measuring chambers through passageways 24 cooperate to cause unidirectional movement of shaft 30. An example of such meter mechanism is shown in a copending application of Arthur S. McIntire, Serial No. 219,851.

The present improvements are specifically concerned with the construction of the composite disk 20 which produces advantages over the construction shown in my aforesaid Patent No. 1,586,685.

As in my former said patent the glass ring 21 of this improved valve disk is topped by a thin sheet metal cap 37 having an upwardly dished central portion whose roof wall 38 spans the circular opening 39 in the glass ring 21 and supports centrally thereof the boss 34. The impelling force imparted to boss 34 by the crank pin 32 brings into play a tendency of the roof wall 38 to warp or distort when the cap 37 is made of thin enough metal to be desirably light in weight. Nevertheless, there is not room below the register driving mechanism 14 to impart a dome-shape contour to the roof wall 38 for strengthening it and it is undesirable to add extra parts for purposes of reinforcement since this complicates the structure and increases the weight of the composite disk. It is of great importance to keep the disk weight as light as possible in order to minimize wear and the retarding effect of friction between the bottom surfaces of the glass ring 21 and the top edge seats of partition walls 22 upon which said ring rides with its weight supported thereon. Another problem to be solved is the retention of oil and dirt which may drop on the valve disk from mechanism 14 or be precipitated thereupon from the gas flowing through the meter head 11. Such oil and foreign matter must be prevented from working radially outward and then downward

over the edge of the disk and thus becoming deposited on the top edge seats of the partition walls because an accumulation thereof would impair the gas tight seal which must always be maintained between these edges and the bottom surface of the gyratory glass ring 21.

To accomplish these objects I have embossed one or more depressions in the diaphragm-like wall 38 between boss 34 and the rim 43 disposed to extend about the former. Specifically herein, these curved embossings are illustrated as one or more concentric corrugations, 41 and 42 which form ring-like troughs. Whether or not circularly complete, these corrugations are found to add to the rigidity with which boss 34 is held in relation to the apertured disk body 21 and they also serve as separate annular catch pockets for oil precipitated upon the roof wall 38 of the cap or dropped thereupon or conducted thereto from the mechanism 14 along the crank finger 18.

I further indent the material of cap 37 to form an upstanding bead 44 herein illustrated as circular and of greater circumference than either of the corrugations 41 or 42 and surrounding the latter. Bead 44 is proximate the peripheral edge of the disk and serves to guard against deposits of oil or foreign substances which may have escaped the corrugations 41, 42, or which may have become deposited originally on the cap radially outside the latter, from working outward and reaching the peripheral edge of the cap under the urge of the centrifugal force set up by the gyratory movement of the disk.

It will be noted that the peripheral edge of the ring like body 21 has a cross sectional contour in a diametral plane as viewed in Fig. 4 which is convexly arched and thereby imparts a crown shape to such edge, and that cap 37 is provided with a down-turned rim 43 which is spun or otherwise forced into close hugging or mechanical holding conformity with such convexly arched contour of the crown-shaped edge. For further insuring absolute fixity of cap 37 in relation to the ring body 21, suitable kinds of cement which will be chemically impervious to all ingredients of the gas passing through the meter may be applied between the cap and the top surface of the ring body before they are mechanically assembled.

The operation of a valve disk embodying the present improvements has been explained in connection with the foregoing description of the novel features of the construction. The following claims will be understood as directed to and intended to cover all fair equivalents of the particular parts and details of construction herein chosen to illustrate a preferred form of the invention.

I claim:

1. In a valve disk structure for gas meters adapted to perform edgewise gyratory movement in a horizontal plane, at least one trough sunk in the top surface of said structure extending about the center of said disk for trapping foreign substances and preventing said substances from being forced outward by centrifugal force to the peripheral edge of said disk.

2. In a valve disk structure for gas meters adapted to perform edgewise gyratory movement in a horizontal plane, a ridge upstanding from the top surface of said structure extending about the central portion of said disk for trapping foreign substances thereby to prevent the latter from being flung outwardly by centrifugal force to the peripheral edge of said disk.

3. In a valve disk structure for gas meters adapted to perform edgewise gyratory movement in a horizontal plane, at least one trough sunk in the top surface of said structure, and a ridge upstanding from the top surface of said structure, said trough and ridge both extending about the center of said disk in radially differing relationship for trapping foreign substances at different radial distances and thereby preventing them from being flung outwardly by centrifugal force to the peripheral edge of said disk.

4. A composite valve disk adapted to perform gyratory movement edgewise for opening and closing valve ports, embodying in combination, a self rigid valve body containing a central aperture, a cap of relatively thin sheet-like material overlying and fixed on the top face of said body having a diaphragm-like portion spanning said aperture, a boss carried by said diaphragm-like portion adapted to be actuated for impelling said composite valve disk to perform its said movements, and a circuitous trough indented in said diaphragm-like portion of the cap extending about said boss for catching and retaining vagrant oil or foreign substances deposited on the top of said cap in the vicinity of said boss.

5. A composite valve disk adapted to perform gyratory movement edgewise for opening and closing valve ports, embodying in combination, a self rigid valve body containing a central aperture, a cap of relatively thin sheet-like material overlying and fixed on the top face of said body having a diaphragm-like portion spanning said aperture, a boss carried by said diaphragm-like portion adapted to be actuated for impelling said composite valve disk to perform its said movements, and a plurality of corrugations comprising separate concentric circular troughs surrounding said boss formed in said diaphragm-like portion of the cap in a manner to stiffen the support of said boss with respect to said valve body and to trap vagrant oil and foreign substances for preventing them from reaching the outermost circumferential rim of said cap.

6. A composite valve disk adapted to perform gyratory movement edgewise for opening and closing valve ports, embodying in combination,

a self rigid valve body containing a central aperture, a cap of relatively thin sheet-like material overlying and fixed on the top face of said body having a diaphragm-like portion spanning said aperture, a boss carried by said diaphragm-like portion adapted to be actuated for impelling said composite valve disk to perform its said movements, a circuitous bead embossed upwardly in the material of said cap proximate the radially outermost rim thereof in a manner to form a completely surrounding retaining ridge for preventing vagrant oil or foreign substances lodged on the top of said cap from reaching said rim of the cap.

15 7. A composite disk for opening and closing valve ports in a gas meter, embodying in combination, a self rigid circular valve body having a top face surrounding a central aperture in said body and having a peripheral edge whose cross sectional contour in a diametral plane is convexly arched thereby to impart a crown shape to said edge, a cap of sheet-like material overlying the top face of said body having a corrugated central diaphragm-like portion spanning said aperture and a downward turned rim portion shaped to conform to the convexly arched contour of said edge in a manner closely to hug the latter thereby to interlock mechanically therewith.

20 8. A composite disk for opening and closing valve ports in a gas meter, embodying in combination, a self rigid circular valve body having a top face surrounding a central aperture in said body and having a peripheral edge whose cross sectional contour in a diametral plane is convexly arched thereby to impart a crown shape to said edge, a cap of sheet-like material overlying the top face of said body embodying a dished member including a circularly corrugated 35 central roof wall portion joined to and axially offset from a circularly corrugated mounting wall portion bordering said roof wall portion and having a downwardly turned rim portion shaped to conform to the convexly arched contour of said edge in a manner closely to hug the latter thereby to interlock mechanically therewith.

GEORGE H. MOLDEN.
